UNITED STATES PATENT OFFICE.

WILLIAM L. FITCH, OF CHICAGO, ILLINOIS, ASSIGNOR, BY DIRECT AND MESNE ASSIGNMENTS, TO D. H. FLETCHER, TRUSTEE, OF SAME PLACE.

AIR-SUPPLY TO THE FEED-WATER FOR STEAM-BOILERS.

SPECIFICATION forming part of Letters Patent No. 285,884, dated October 2, 1883.

Application filed December 23, 1882 (No model.)

To all whom it may concern:

Be it known that I, WILLIAM L. FITCH, a citizen of the United States, and residing at Chicago, in the county of Cook and State of Illinois, have invented certain new and useful Improvements in Air-Supply to the Feed-Water for Steam-Boilers, which are fully set forth in the following specifications.

It has heretofore been observed that more heat is required to produce a given pressure in a boiler from water from which all the air has been exhausted by repeated boilings than from water which contains a considerable quantity of absorbed air, commonly called "live water."

My invention consists in providing an economical method of introducing air into steam-boilers, and in certain preferred forms of devices for putting that method into practice.

My method consists in charging the water, before it enters the boiler, with air to as great a degree as possible without preventing the proper action of the pump or other feeder which forces the water to the boiler. The preferred forms of device for so charging the water are hereinafter set forth. The extent to which the water may be so charged will vary somewhat with different feeders; but preferably the amount of air introduced should not be more than the water will receive by absorption or hold in minute globules, and without any strong tendency to separate before the water reaches the boiler.

Figure 1 shows the application of my invention and device to a steam-pump employed to force water to a steam-boiler. Fig. 2 shows the application of the same invention and device to a feeder of the class known as an "inspirator."

A, Fig. 1, is the pump-cylinder. A', Fig. 2, is a familiar form of inspirator. B is each is the water-induct pipe. C is the discharge-pipe leading to the boiler. D is an air-feed pipe, which opens into the water-supply pipe B at any convenient point, preferably between the reservoir and the feeder,—pump or injector; but a valve, G, should be employed, located between the reservoir and the air-feed pipe D,

to regulate the supply of water from the reservoir. Such a valve is commonly employed, 50 and it is not a part of my invention.

The air-feed pipe D may, in some circumstances, be located opening into the inspirator, as indicated by the outline H, between the primary and secondary steam-jet of the inspirator; or it may, though even less preferably, be connected between the inspirator or injector and the boiler, as indicated by the outline K; but I deem the preferable location to be as first above described—between the reservoir 55 and the feeder. In whatever position it is placed, the opening of the air-feed pipe D into the water-supply pipe B should preferably be controlled by a valve, E, by means of which the amount of air admitted may be regulated. 65

F is a check-valve in the air-feed pipe, which opens inward, admitting air when the feeder is drawing water, and closing to prevent the escape or discharge of water by pressure from the reservoir or otherwise at the counter or 70 forcing stroke of the pump-piston. When a pump is the feeder employed, or at any instant when the feeder is not drawing water through the water-induct pipe B, this valve is a convenience only, not a necessity. The action of 75 this device is that the current of water drawn by the feeder through the pipe B will induce a suction of air through the pipe D, the opening into which may be so regulated by the valve E that the amount of air taken shall be 80 only such as the water will absorb or hold in suspension in minute globules, so not preventing the action of the pump drawing by suction and not forming an air-cushion in the pump-cylinder sufficient to prevent the action 85 of the pump-piston forcing the water forward to the boiler. When an injector or inspirator is the feeder employed, the difficulty above suggested, possible to arise in the use of a pump, will not be experienced, and the amount of air 90 taken will consequently not be so limited. The air thus taken passes with the water to the boiler, and, being there heated with the water, adds its expansive force to that of the water, and, as proven by experience, makes it possible to obtain, with less water and less consump-

tion of fuel, a greater available force for motive power and a greater amount of steam for heating purposes than if water alone were fed to the boiler.

5 The purpose served by the valve E is to regulate the amount of air admitted to the water-supply pipe in such ratio to the amount of water admitted through the valve G that the maximum effectiveness of the combination for 10 steam or pressure producing purposes may be attained. Just at what point this maximum is found will vary with the varying circumstances of each case, as the character of the feeder employed, the pressure of steam maintained, the presence and character of impurities in the water, and, perhaps, other circumstances, and, besides, the purpose and use to which the steam is being applied will be taken into account. If dry steam is desired, more 15 air will be taken, and if wet steam less, and without special or further instruction any experienced engineer will make the proper adjustment, according to the needs of the case.

Air and water have heretofore been heated 20 in the same boiler for the purpose of securing the combined advantages of steam and hot-air pressure; but it has been usual to feed the air and water to the boiler by separate conduits, so requiring separate feeding devices and encountering other difficulties. The result has 25 been that the amount of power expended to operate these devices has been nearly or quite equal to the gain effected by them.

The advantages of our method—viz., charging 30 the water with air before feeding it to the boiler—are economy of construction, simplicity of operation, and that absolutely no power additional to that required to pump the water

is needed to take also the air, so that the advantage of the presence of the air in the boiler 40 is a total gain. In addition, when a pump is the feeder employed, the presence of air in the water when it reaches the pump-cylinder renders it somewhat elastic, being inflated by the air, and thereby eases the pump, preventing 45 the "pounding," so often unavoidable when pumping "solid" water.

I claim, therefore, as my invention and desire to secure by Letters Patent—

1. The method of supplying air to steam-boilers, which consists, substantially, in charging the feed-water, before it passes to the boiler, with air.

2. The method of charging with air the feed-water for steam-boilers, which consists in admitting the air in limited quantity to the water-supply pipe to the feeder.

3. In the water-supply pipe to a feeder to a steam-boiler, an opening provided for the purpose of admitting air thereto, controlled by 60 suitable valve or valves, substantially as set forth.

4. In combination with the water-supply pipe B, the air-induct pipe D, provided with the valve E, substantially as and for the purpose set forth.

5. In the described air-inductor, and in combination therewith, the check-valve F, substantially as and for the purpose set forth.

In testimony that I claim the foregoing as 70 my invention I have hereunto set my hand in the presence of two witnesses.

WM. L. FITCH.
